UNITED STATES PATENT OFFICE.

CHARLES PACK, OF ELMHURST, NEW YORK, ASSIGNOR TO DOEHLER DIE-CASTING CO., A CORPORATION OF NEW YORK.

DIE-CASTING APPARATUS.

Application filed October 27, 1923. Serial No. 671,084.

My invention relates to the art of die casting of metals and more particularly to the mechanism in a die casting apparatus for containing the molten metal and delivering it to the die under pressure.

There are two general types of such mechanisms, one in which the metal is delivered directly from the melting pot to the die, and the other in which a suitable charging pot or ladle operates automatically to obtain a charge of the molten metal from the melting pot and to deliver the same to the die. It is the more common practice to employ a pressure fluid, such as compressed air, to develop the pressure upon the metal, either in the melting pot in the first type of mechanism, or in the charging pot or ladle in the second type of mechanism, to force the metal through the gate opening into the die.

Obviously, a mechanism in which the metal is delivered directly from the melting pot to the die is in some respects preferable. It has the advantage of simplicity in that no ladle filling mechanism is required operating either to submerge a movable ladle within the molten metal and then bring the ladle into registry with the gate opening to discharge its contents within the die, or, with the ladles in the form of a stationary charging pot disposed within the molten metal and having its mouth registering with the gate opening, operating to open and close a controlling valve to admit molten metal to the charging pot. It does not have the surfaces, both interior and exterior, of the ladle to be attacked by the casting alloy, and for this reason less impurities are contained within the casting metal.

However, the type of mechanism in which the metal is delivered directly from the melting pot to the die, in the forms heretofore proposed, has had certain well recognized disadvantages. It has been found impossible to obtain a valve construction controlling the admission of the molten metal to the die, which could withstand the deleterious action of the casting alloy for any substantial period of time. Furthermore, this type of mechanism has necessitated the exposing of a large surface of the molten metal to the pressure fluid and the resultant formation of undue quantities of oxides and other dross. On the other hand, the charging pot type of construction has the advantage that the pressure fluid comes in momentary contact only with that quantity of the molten

metal which is being forced within the die from the charging pot. The disadvantages of the direct type of apparatus heretofore proposed have been sufficient to prevent their practical use to any considerable extent, and for this reason, the charging pot type of mechanism has almost universally been employed despite its shortcomings, referred to above. The desirability of a satisfactory direct charging type of mechanism which would dispense with the charging pots or ladles, has long been recognized, but to my knowledge none has heretofore been produced.

It is an object of my invention to provide a mechanism for containing the molten metal and delivering it directly under pressure as desired to the die, which will be free from the disadvantages of that type of mechanism above enumerated, while preserving all of the advantages inherent in that type of mechanism. Another object is to provide a mechanism for automatically replenishing the metal in the melting pot as it used for casting so as to keep the level of the metal in the pot substantially constant. Still other objects and advantages of my invention will appear from the following description.

In accordance with my invention I employ a melting pot having a discharge spout connecting with the bottom of the pot, the discharge nozzle of which is above the normal level of the metal in the melting pot, and registers with the gate opening which may be, for example, in one of the die clamps and thence through the adjacent die part, or, as in some types of mechanism, at the parting line of the die parts. In other words the melting pot approximates a U-shape, being generally of the form of the goose-neck ladles employed in connection with melting pots in the die casting industry. The size of the melting pot will be determined by the rate at which the metal is used, its capacity being such that the temperature of the molten metal will not be materially reduced by the melting of ingots fed to the pot at proper intervals to maintain the level of the metal substantially constant. In order to force a charge of the metal into the die for each casting operation, means are provided for delivering pressure fluid, such as compressed air, upon the top of the metal.

This form of melting pot dispenses with

the need for valves to control the connection between the melting pot and the gate opening. It will be appreciated that it is desirable to maintain the level of the metal within the pot as near as possible to the discharge opening or nozzle of the pot. As the level of the metal recedes within the spout a larger air chamber at the nozzle end is thereby provided with the result that more air is forced within the die as the metal is expelled through the nozzle, which tends to form blow-holes in the casting. Furthermore as the level of the metal falls the size of the air chamber in the top of the melting pot increases. Since this chamber is in effect an expansion chamber for the air, it is manifest that economy demands that its size be kept as nearly constant as possible. My invention, therefore, contemplates means for automatically maintaining this level approximately constant. In accordance with my invention I provide a mechanism which is automatically controlled by the casting operation itself for replenishing the metal within the pot at such intervals as is required to prevent the level of the metal from falling substantially below the nozzle opening. Preferably I provide automatic means for feeding ingots of the casting alloy to the pot as required. Manifestly, as the rate of metal consumption varies, it will be necessary correspondingly to vary the frequency at which the ingots are fed to the melting pot, and in accordance with my invention, the automatic feeding means which is controlled by the casting operation is susceptible of adjustment or change so as to regulate the relative frequency of the feeding operation.

My invention contemplates other features of construction and details and arrangement of parts, as will hereinafter more fully appear. I shall now describe the illustrated embodiment of my invention and shall thereafter point out my invention in claims.

Fig. 1 is a side elevation partially in section of an apparatus which embodies my invention;

Fig. 2 is a sectional detail on an enlarged scale, taken on line 2-2 of Figure 1;

Fig. 3 is an enlarged detail showing in section a fragment of the sprocket chain with one of the impulse fingers secured thereto.

The base 1 of the apparatus supports at its one end a furnace 2 resting upon which is the melting pot 3. This melting pot is roughly of a U-shape, the discharge leg of which is smaller than the main body of the pot and partakes generally of the form of the spout terminating in a laterally extending discharge nozzle 4. The top of the pot is closed by a plate 5 through which enters a pipe 6 for compressed air or other

pressure fluid controlled by a hand valve 7. Mounted on the bed of the base 1, are supports for the die clamps and the mechanism for opening and closing the die. Longitudinally of the bed of the base extend one or more guide rails 8, upon which slide the clamp member 9 for the gated half of the die and a bracket plate 10 connected to the clamp 9 by rods 11. Guided upon these rods 11 is the clamp member 12 for the other half of the die which is connected to the bracket member 10 by a toggle consisting of the link 13 pivoted at its forward end to a lug on the rear face of the clamp member 12, and link member 14 which is pivoted at one end to the link 13 and at its other end to a lug on the front face of the bracket member 10. The rear pivot 15 for the link 14 is a short stub rock shaft on which the link 14 is secured and to the opposite end of which is secured a pinion 16. This pinion engages with a rack 17 secured on the bed of the base 1. The clamp member 9 for the gated half of the die has the gate opening through a boss 18 which is adapted to register with the nozzle 4 when the die support is in the casting position shown. It is evident that as the bracket member 10 is retracted, it will withdraw the die support away from the nozzle 4 and at the same time will open the die by retracting the clamp member 12 relative to the clamp member 9. This die opening operation is effected by the breaking of the toggle 13, 14 due to the rotation of the pinion 16 upon the rack 17. It is also apparent that the reverse movement of the bracket member 10 will again close and lock the die due to the reverse rotation of the pinion 16 on the rack 17 and the consequent locking of the toggle 13, 14. This die opening and closing mechanism is similar to that claimed in the co-pending application of Marc Stern, filed May 24, 1924, Serial No. 715,712, and forms no part of my invention.

Any suitable mechanism may be employed for operating the bracket member 10 to open and close the die. In the construction illustrated I have shown a compressed air motor 19 which operates the connecting rod 20 attached to the rear face of the bracket member 10.

The automatic ingot feeding mechanism controlled by the casting operation so as to operate in properly timed relation thereto, will now be described.

Supported upon a standard 21 arising from the bed of the base 1 are two sprocket wheels 22 and 23 which are connected by a sprocket chain 24. On the cross pins of this sprocket chain are removably secured a plurality of impulse fingers 25. As shown, these impulse fingers extend out some distance beyond the face of the chain, and

their attaching parts are of just the right length to span the hubs of two adjacent cross pins of the chains. The ends of the attaching parts of the impulse fingers are accurate, one end going substantially half way round its hub and the other end going less than half way round so as to permit of the ready application of the finger, the shorter end being secured to its hub by a set screw. It will thus be understood that the number of these fingers can readily be increased or decreased.

These fingers 25 are arranged to actuate a horizontal push rod 26 which is supported at one end in an arm 27 extending up from the standard 21 and its other end in a standard 28 rising from the base adjacent the furnace 2. This push rod is normally retracted by a spring 29 which bears at one end against the standard 28 and with its other end against a collar on the push rod 26.

This push rod 26 operates an escapement mechanism to release an ingot with each actuation of the push rod. In the form shown, the ingots 30 are contained in a vertical chute 31 which leads through the plate 5 into the top of the pot. The ingots are of cylindrical form with a reduced lower end so as to provide a shoulder for the engagement of the escapement mechanism. A link 32 is pivoted at its centre to a lug on the top of the standard 28 and has a slotted opening in its upper end which engages over a pin on the push rod 26. Below its pivot the link 32 carries, by a slotted connection, a finger 33 which extends through an opening in the chute 31, as does the end of the push rod 26. In the retracted position of the push rod 26, the finger 33 is advanced and engages underneath the shoulder of the lowermost ingot 30. As the push rod 26 is impelled inwardly against the tension of the spring 29 the finger 33 is withdrawn, thereby releasing the lowermost ingot 30, while the end of the push rod is simultaneously caused to engage underneath the ingot 30 immediately above the lowermost one, and thus hold it and those above it from following the lowermost ingot as it falls into the pot 3.

A suitable gate mechanism, shown in Figure 2, is provided in the chute underneath the lowermost ingot. This gate is automatically opened when the lowermost ingot is released and is again closed as the spring 29 returns the push rod to its outward position, thereby serving to close the compression chamber above the metal in the pot when the valve 7 is opened and the pressure fluid admitted. In the form shown, the chute 31 has a transverse enlargement 34 within which is a horizontal swinging closure disc 35 on one end of a pivoted bell crank 36. The other end of

the bell crank is connected to a link 37 to the outer end of which is pivoted a link 38 forming a continuation at its upper end with the lower end of the link 32. In Figure 2 the gate is shown in its closed position, which is the position it occupies when the push rod is retracted as shown in Figure 1. As the push rod 26 is advanced by an impulse finger 25, the movement of the link 32 of the escapement mechanism actuates the bell crank 36 through the links 37 and 38 and swings the closure 35 in a clockwise direction, as viewed in Figure 2 and uncovers the passage through the chute 31.

The sprocket wheels 22 and 23 may be actuated in any convenient way by any part of the mechanism employed in the casting operation. In the construction shown they are arranged to be actuated by the movement of the parts in opening the die. On the upper sprocket wheel 22 is a ratchet wheel 39 which is engaged by a ratchet 40 on the upper end of an arm 41 loosely pivoted upon the axis of the ratchet wheel 22. This arm 41 extends down into the path of the upper rod 11 and these parts are so related that as the bracket member 10 and the rods 11 are retracted by the motor 19, the rod 11 which engages the arm 41 will swing the arm around in a clockwise direction and actuate the ratchet wheel 39 a predetermined distance. The weight of the arm 41 will cause it to fall again to a vertical position when the die is closed, thus retracting the ratchet 40 for another actuation.

The actuation of the ratchet wheel 39 rotates the sprocket wheel 22 a corresponding distance and hence correspondingly advances the sprocket chain 24. It is evident that the number of actuations of the arm 41 required to cause an actuation of the push rod 26 depends upon the number of impulse fingers 25. As an illustration, suppose that the pot 30 contains 250 pounds of metal when it is just full up to the nozzle opening, and that each casting takes 2 ounces of metal and that an ingot weighs 2 pounds. It is evident that in 16 casting operations, 2 pounds of the metal will be used and if immediately following the 16th casting operation a 2 pound ingot is added to the melting pot, the metal will have been restored to its former level. The impulse fingers 25 will then be so spaced and the throw of the arm 41 will be so determined that the fingers 25 will give an impulse to the push rod 26 after every 16 actuations of the arm 41. If

the casting should take a little less than 2 ounces of metal, then the spacing between the fingers 25 will be correspondingly adjusted, or, for instance, one of the fingers 25 might be removed altogether so as to omit the feeding of an ingot once for every complete rotation of the chain 24. Similar

ly, the spacing between the fingers could be adjusted to take care of castings which took slightly more than 2 ounces of metal or for ingots which contained a little more or a little less than 2 pounds of metal, or for any other condition which would arise in casting experience.

With a pot of molten metal of sufficient quantity, the addition of an ingot intermittently in the manner above described will not affect the temperature of the molten metal materially. The oxides and other dross formed by the contact of the air with the surface of the metal will always remain on the top of the metal and by reason of the relatively small diameter of the pot due to its length, the surface attacked by the air is relatively small.

It will be understood that the above described apparatus is only intended to be illustrative of one way in which my invention may be embodied and that various other ways of carrying out the principle of my invention, as above explained, will readily occur to those skilled in the art without departing from the spirit of the invention or the scope of the appended claims.

I claim:

1. In a die casting apparatus, in combination with a die support including two separable clamps, a melting pot for the casting metal having a discharge nozzle adapted to feed the molten metal directly to the die, means for delivering pressure fluid on top of the molten metal in the pot to expel a quantity thereof through the nozzle into the die, means for separating the clamps to open the die, and means controlled thereby for feeding ingots to the melting pot at desired intervals relative to the operations of the clamp separating means.

2. In a die casting apparatus, in combination with a die support including two separable clamps, a melting pot for the casting metal having a discharge nozzle adapted to feed the molten metal directly to the die, means for delivering pressure fluid on top of the molten metal in the pot to expel a quantity thereof through the nozzle into the die, means for separating the clamps to open the die, means controlled thereby for feeding ingots to the melting pot at desired intervals relative to the operations of the clamp separating means, and means for varying the relative frequency of the ingot feeding operations.

3. In a die casting apparatus, in combination with a die support, a substantially U-shape melting pot for the casting metal terminating in a discharge nozzle adapted to feed molten metal directly to a die in the die support, means for delivering pressure fluid on top of the molten metal in the pot to expel metal through the nozzle, automatic means for intermittently replenishing the

metal in the pot through the pressure fluid end, and means for varying the relative frequency of the replenishing operations.

4. In a die casting apparatus, in combination with a die support including two separable clamps, a substantially U-shaped melting pot terminating in a discharge nozzle adapted to feed molten metal directly to a die in the die support, means for effecting repeated casting operations including the delivery of pressure fluid on top of the molten metal in the pot to expel a quantity thereof through the nozzle into a die in the die support and operating the die clamps to open and close the die, and means controlled by the casting effecting means for automatically feeding ingots to the pot through the pressure fluid end at desired intervals relative to the casting operations.

5. In a die casting apparatus, in combination with a horizontally disposed die support including two separable clamps, a stationary substantially U-shaped melting pot terminating in a discharge nozzle adapted to feed molten metal directly to a die in the die support, means for effecting repeated casting operation including the delivering of pressure fluid on top of the molten metal in the pot to expel a quantity thereof through the nozzle into a die in the die support and operating the die clamps to open and close the die, means controlled by the casting effecting means for replenishing the metal in the pot through the pressure fluid end at desired intervals relative to the casting operations, and means for varying the relative frequency of the replenishing operations.

6. In a die casting apparatus, in combination with a horizontally disposed die support including two separable clamps, a stationary substantially U-shaped melting pot terminating in a discharge nozzle adapted to feed molten metal directly to a die in the die support, means for delivering pressure fluid on top of the molten metal in the pot to expel a quantity thereof through the nozzle into a die in the die support, means for separating the clamps to open the die, and means controlled by the clamp separating means for feeding ingots to the pot through the pressure fluid end at desired intervals relative to the casting operations.

7. In a die casting apparatus, in combination with a horizontally disposed die support including two separable clamps, a stationary substantially U-shaped melting pot terminating in a discharge nozzle adapted to feed molten metal directly to a die in the die support, means for delivering pressure fluid on top of the molten metal in the pot to expel a quantity thereof through the nozzle into a die in the die support, means for separating the clamps to open the die, means controlled by the clamp separating means

- for feeding ingots to the pot through the pressure fluid end at desired intervals relative to the casting operations, and means for varying the relative frequency of the 5 ingot feeding operations.
8. In a die casting apparatus, in combination with a horizontally disposed die support including two separable clamps, a stationary substantially U-shape melting pot terminating in a discharge nozzle adapted to feed molten metal directly to a die in the die support and proportioned to contain a large mass of molten metal relative to that required for each casting, means for delivering 10 pressure fluid on top of the molten metal in the pot to expel a quantity thereof through the nozzle into a die in the die support, automatic means for feeding ingots to the pot through the pressure fluid end, 15 and means for controlling the rate of feeding in accordance with the number of casting operations, whereby the level of the metal in the pot is maintained substantially constant.
- 20 9. In a die casting apparatus, in combination with a die support including separable clamps, a melting pot provided with a discharge nozzle and proportioned to contain a large mass of metal relative to that required for each casting, means for delivering 25 pressure fluid on top of the molten metal in the pot to expel a quantity thereof through the nozzle into the die, automatic means for feeding ingots to the pot through the pressure fluid end, and means for controlling the rate of feeding in accordance 30 with the number of casting operations for thereby maintaining the level of the metal in the pot substantially constant.
- 35 10. In a die casting apparatus, in combination with a die support including separable clamps, a pressure chamber forming a melting pot for the casting metal provided with a discharge nozzle, means for effecting 40 repeated casting operations including means for delivering pressure fluid on top of the molten metal in the pot to expel a quantity thereof through the nozzle into the die and operating the clamps to open and close the 45 die, and means controlled by the casting effecting means for automatically feeding ingots to the pot at desired intervals relative to the casting operations.
- 50 11. In a die casting apparatus, in combination with a die support including separable clamps, a pressure chamber forming a melting pot for the casting metal provided with a discharge nozzle, means for effecting 55 repeated casting operations including means for delivering pressure fluid on top of the molten metal in the pot to expel a quantity thereof through the nozzle into the die and operating the clamps to open and close the die, means controlled by the casting effecting 60 means for automatically feeding ingots to the pot at desired intervals relative to the casting operations.
- 65 to the pot at desired intervals relative to the casting operations, and means for varying the relative frequency of the ingot feeding operations.
12. A die casting machine having, in combination, a pressure chamber forming a melting pot for metal to be cast provided with a discharge nozzle, means for delivering pressure fluid on top of the molten metal in the pot to expel a quantity thereof 70 through the nozzle into a die, and means for feeding ingots to the pot comprising a closure for the top of the pot operable to open and close the pot, a device operable to feed an ingot into the open pot, and means for compelling the operation of said closure and said device in proper timed relation relatively to each other for successively opening the pot, feeding the ingot thereto 75 and closing the pot. 85
13. A die casting machine having, in combination, a pressure chamber forming a melting pot for metal to be cast provided with a discharge nozzle, means for delivering pressure fluid on top of the molten metal in the 80 pot to expel a quantity thereof through the nozzle into a die, and means for feeding ingots to the pot comprising a closure for the top of the pot operable to open and close the pot, a device operable to feed an ingot 85 into the open pot, and operating means for assuring and effecting the operation of said closure and said device in timed sequence relatively to each other for successively opening the pot, feeding the ingot thereto 90 and closing the pot, in the order named. 100
14. A die casting machine having, in combination, a pressure chamber forming a melting pot for metal to be cast provided with a discharge nozzle, means for delivering pressure fluid on top of the molten metal in the pot to expel a quantity thereof through the nozzle into a die, and a metal-replenishing feed mechanism to feed ingots to the pot automatically at predetermined times 105 relatively to the casting operations, said feed mechanism comprising a closure for opening and closing the pot at the top thereof, a device adapted to be operated to feed an ingot into the open pot, and means for operating 110 the closure and said device in proper timed relation relatively to each other and relatively to the casting operations. 115
15. A die casting machine having, in combination, a pressure chamber forming a melting pot for metal to be cast provided with a discharge nozzle, means for delivering pressure fluid on top of the molten metal in the pot to expel a quantity thereof 120 through the nozzle into the die, and a metal-replenishing feed mechanism to feed ingots to the pot automatically at predetermined times 125 relatively to the casting operations, said feed mechanism comprising a closure for opening and closing the pot at the top 130

- thereof, a device adapted to be operated to feed an ingot into the open pot, and means for operating the closure and said device in proper timed relation relatively to each other and relatively to the casting operations, said operating means including means for varying the frequency of the ingot feeding operations relatively to the casting operations as desired.
- 10 16. A die casting machine having, in combination, a pressure chamber forming a melting pot for metal to be cast provided with a discharge nozzle, means for effecting relative movement between the pot and a die 65 to and from casting relation, means for delivering pressure fluid on top of the molten metal in the pot to expel a quantity thereof through the nozzle into the die, and a metal-replenishing feed mechanism to feed ingots 70 to the pot automatically at predetermined times relatively to the casting operations and while the pot and the die are out of casting relation, said feed mechanism comprising a closure for the top of the pot operable to open and close the pot, a device operable to feed an ingot into the open pot, and means controlled by a moving part of the machine for automatically operating said closure and said device at the proper time to 75 open the pot, feed an ingot thereto and close the pot all between the times in which the die and the pot are in casting relation.
17. A die casting machine having, in combination, a pressure chamber forming a melting pot for metal to be cast provided with a discharge nozzle, means for effecting relative movement between the pot and a die to and from casting relation, means for delivering pressure fluid on top of the molten metal in the pot to expel a quantity thereof through the nozzle into the die, and a metal-replenishing feed mechanism to feed ingots to the pot automatically at predetermined times relatively to the casting operations and 80 while the pot and the die are out of casting relation, said feed mechanism comprising a closure for the top of the pot operable to open and close the pot, a device operable to feed an ingot into the open pot, and means controlled by a moving part of the machine for automatically operating said closure and said device at the proper time to open the pot, feed an ingot thereto and close the pot 85 all between the times in which the die and the pot are in casting relation.
18. A die casting machine having, in combination, a pressure chamber forming a melting pot for metal to be cast provided with a discharge nozzle and a metal-replenishing feed mechanism operated automatically in proper timed relation to the casting operations to feed ingots to the pot at predetermined times relatively to the casting operations.
19. A die casting machine having, in combination, a pressure chamber forming a melting pot for metal to be cast provided with a discharge nozzle, and a metal-replenishing feed mechanism operated automatically in proper timed relation to the casting operations to feed ingots to the pot at predetermined times relatively to the casting operations, said feed mechanism including means for varying the number of ingot feeding operations relatively to the number of casting operations.
20. A die casting machine having, in combination, a pressure chamber forming a melting pot for metal to be cast provided with a discharge nozzle, and a metal-replenishing feed mechanism operated automatically in proper timed relation to the casting operations to feed ingots to the pot at predetermined times relatively to the casting operations, said feed mechanism comprising an ingot-feeding device adapted when operated to feed an ingot to the pot, means for operating the ingot-feeding device including a lug carrier the lugs of which control the operations of said device, means for automatically advancing the lug carrier a step at each casting operation, and settable lugs adapted to be set to different positions on the lug carrier for causing the ingot-feeding device to be operated at predetermined casting operations only and whereby the frequency of the ingot feeding operations relatively to the casting operations may be varied as desired.

In testimony whereof, I hereunto subscribe my signature.

CHARLES PACK.
